EARL D. WILSON, OF WILKINSBURG, PENNSYLVANIA, ASSIGNOR TO WESTINGHOUSE ELECTRIC & MANUFACTURING COMPANY, A CORPORATION OF PENNSYLVANIA

LIGHT-SENSITIVE DEVICE

Application filed April 23, 1930. Serial No. 446,515.

This invention relates to light-sensitive devices and especially to gas-filled phototubes adapted to be operated at the ionizing potential of the gas.

5 An object of the invention is to operate a gas-filled tube in a system in which high-vacuum phototubes have heretofore been used. More specifically, it is an object of the invention to operate a gas-filled phototube at 10 the ionizing potential of the gas therein and to obtain thereby the operating characteristics of high-vacuum phototubes.

Commercial phototubes have heretofore been rated to be operated at 90 volts potential 15 drop across the electrodes and load resistance. These tubes have been marketed in two distinct classes. The first class is a high-vacuum tube which is operated in the absence of all gas. These high-vacuum tubes are especially adapted for linear measurements, as 20 the current is proportional to the light falling on the cell. Consequently, these tubes heretofore have been used in all calibrated photometric instruments using phototubes. The 25 current output of a high-vacuum tube is constant, in respect to voltage, provided the voltage is greater than a certain minimum value. In other words, the current-voltage curve is substantially a horizontal line after the first 30 initial rise. However, it is sometimes difficult to make consistently sensitive vacuum tubes in quantity production.

Tubes of the other class are gas-filled, the gas being, generally, argon, at a pressure of 35 100 to 125 microns. At its rated potential of 90 volts, the gas-filled tube is extremely sensitive and, therefore, is used in sound moving-pictures and also in the detection of small quantities of light.

40 The gas-filled tube, at its rated voltage, is approximately ten times as sensitive to light as the vacuum tube. However, the gas-filled tube, at its rated voltage, decreases in effective sensitivity as the frequency of modulation 45 of the incident light increases.

The vacuum tube, on the other hand, is equally effective at all frequencies. The current in a gas-filled tube, at its rated voltage, is critically dependent on the actual value of 50 the voltage, while, as explained above, in a

high-vacuum tube, the current is independent of the voltage, after a saturated condition is reached.

In view of these different characteristics of the vacuum and gas-filled phototubes, it 55 has been customary to use either the one or the other according to the operating characteristics that were desired. Accordingly, two distinct sets of tubes were required in any up-to-date laboratory using phototubes for various purposes. This invention, however, 60 contemplates a gas-filled tube that can be used in place of the high-vacuum tube, in addition to its use as an ordinary gas-filled tube.

Other objects of my invention will become 65 apparent from the following detailed description, taken in conjunction with the accompanying drawing, in which

Figure 1 is a view, partly in perspective, partly in section and partly diagrammatic, of 70 a phototube and connections thereto;

Fig. 2 is a curve illustrating the voltage-current characteristic of a gas-filled tube;

Fig. 3 is a curve illustrating the voltage-current characteristics of a high-vacuum 75 phototube;

Fig. 4 is a curve illustrating the current-frequency characteristic of a gas-filled tube at various voltages;

Fig. 5 is a curve illustrating a current-frequency characteristic of a high-vacuum tube at various voltages.

In Fig. 1, is disclosed a phototube having a gas-tight container 10, generally of transparent glass, supported on a base 11. Extending through the press 12 of the tube are at least two conductors 13 and 14. To the conductor 13 is attached the cathode 15, preferably in the form of a semi-cylindrical plate attached, at one edge, to the supporting connection 13 and, at the other edge, to an auxiliary support 16. The connection 14 preferably extends up through the axis of the cylindrical cathode 15 and acts as an anode 17. To the upper end of the anode 17 is 80 preferably attached a disc 18 containing a pellet 19 of caesium that has been flashed in the manufacture of the tube to coat the inner surface of the cathode 15 with caesium so that 85 the electrons will be emitted therefrom under 90 100

the influence of light falling upon this inner surface of the cathode. An electrical pressure applied across the cathode 15 and anode 17 will drive the electrons to the anode, with the result that current will flow from the anode 17 to the cathode 15 and thence, through external connections, to the anode 17. The interior of the glass tube 10 is filled with a gas, preferably argon, but, instead of being at the usual pressure, of 100 to 125 microns, this gas is preferably from 75 to 90 microns of pressure.

The tube has the external connectors 20 and 21 to which any desired system may be attached. As disclosed in Fig. 1, a B voltage supply 22 is connected to a potentiometer 23, and a variable tap 24 on the potentiometer is connected to the terminal 20. From the other terminal 21 extends a connection to an amplifier system represented by the amplifier tube 25. This system may include any number of such tubes and may be attached to any desired indicating or recording device. The return connection from the output circuit is represented by the conductor 26. A by-pass condenser 27, a load resistance 28, a grid condenser 29 and a grid leak 30 are suitably inserted in the circuit, as disclosed in the drawing. It is obvious that any suitable circuit may be attached to the terminals 20 and 21 of the tube, but such circuits necessarily include an electrical pressure, such as that provided by the B supply 22 in Fig. 1, for driving the electrons from the cathode to the anode, when light falls on the cathode 15.

In Fig. 2 is disclosed a voltage-current curve for a gas-filled tube such as has been described in connection with Fig. 1. It will be noted that the curve rises sharply to the point 31, then has a flat portion to the point 32 and then begins to curve sharply upward. The rated voltage of a gas-filled tube is generally upon the steep part of the curve. With a high gas pressure inside of the tube, the flat portion of the curve between the points 31 and 32, will be very much shorter and the curve will slope upward more quickly after the point 31 is reached. However, by having the pressure in the tube at from 75 to 90 microns of pressure, instead of the normal 100 to 125 microns, I have provided the longer flat portion on the curve. This flat portion is substantially at the ionizing potential of the gas which is represented by the dotted line 33. For argon gas, this ionizing potential is 15.1 volts. The flat portion 31-32 of the curve represents a voltage range from 13 to 17 volts which is designated as being substantially at the ionizing potential of the gas in the claims appended hereto.

In Fig. 3 is disclosed the voltage-current characteristic curve for a high-vacuum tube. It will be noted that the curve quickly rises to a saturated condition and then becomes

substantially flat. This indicates that the high-vacuum-tube current is independent of the voltage after the saturation point is reached.

In Fig. 4 is illustrated the dynamic characteristic of a gas-filled tube with various voltages. These dynamic characteristics refer to the relative alternating-current response for a given frequency of modulation of the incident light. It will be noted that, at the higher voltages, the response decreases as the frequency increases. However, at a low voltage, which has been found to be substantially the ionizing potential of the gas, such as that illustrated by the dotted line 33 in Fig. 2, the response is constant for practically all frequencies.

In Fig. 5, the curve illustrates the fact that the alternating-current response for all voltages above saturation is independent of the frequency in a high-vacuum tube.

A study of the curves of Figs. 2 through 5 will disclose that a gas-filled tube, such as I have described in connection with Fig. 1 of the drawing, if operated at the ionizing potential of the gas, will give the straight-line characteristics of the high-vacuum tube. According to my discovery, therefore, the gas tube of Fig. 1 can take the place of a high-vacuum tube, provided it is operated at substantially the ionizing potential of its gas. Therefore, it will not be necessary to provide tubes of two different types for use in the various devices that have heretofore required these two types.

Although I have shown and described certain specific embodiments of my invention, I am fully aware that many modifications thereof are possible. My invention, therefore, is not to be restricted except insofar as is necessitated by the prior art and by the spirit of the appended claims.

I claim as my invention:

1. In combination, a light-sensitive device comprising a gas-tight container having a transparent portion, a plurality of electrodes in said container, a light-sensitive surface on one of said electrodes, a gas in said container, said gas being at a pressure of substantially 75 to 90 microns and an electrical potential applied across two of said electrodes at an ionizable potential of said gas.

2. In combination, a light-sensitive device comprising a gas-tight container having a transparent portion, a plurality of electrodes in said container, a light-sensitive surface on one of said electrodes, a gas in said container, and a source of electrical pressure applied to said light-sensitive surface electrode and another of said electrodes, said electrical pressure being substantially at the ionization potential of said gas.

3. In combination, a light-sensitive device comprising a gas-tight container having a transparent portion, a plurality of electrodes

in said container, a light-sensitive surface on
one of said electrodes, a gas in said container,
said gas being at a pressure of substantially
75 to 90 microns, and a source of electrical
pressure applied to said light-sensitive-surface
electrode and another of said electrodes,
said electrical pressure being substantially
at the ionization potential of said gas.

5 In testimony whereof, I have hereunto sub-
10 scribed my name this 18th day of April, 1930.
EARL D. WILSON.
